[57] CLAIM

The ornamental design for a telephone stand, substantially as shown and described.

DESCRIPTION

FIG. 1 is a perspective view of a telephone stand embodying our new design;

FIG. 2 is a top plan view thereof;

FIG. 3 is a bottom plan view thereof;

FIG. 4 is a side elevation view thereof, the opposite side being essentially a mirror image of the side shown;

FIG. 5 is a front elevation thereof;

FIG. 6 is a rear elevation thereof;

FIG. 7 is a perspective view of a second embodiment of the telephone stand illustrated in FIGS. 1-6;

FIG. 8 is a top plan view thereof;

FIG. 9 is a bottom plan view thereof;

FIG. 10 is a side elevation view thereof, the opposite side being essentially a mirror image of the side shown;

FIG. 11 is a front elevation thereof; and

FIG. 12 is a rear elevation thereof.
